2 SHEETS—SHEET 2.

UNITED STATES PATENT OFFICE.

JAMES E. MATTHEWS, OF FARRELL, PENNSYLVANIA.

SLED.

Application filed June 15, 1921. Serial No. 477,723.

To all whom it may concern:

Be it known that I, JAMES E. MATTHEWS, a citizen of the United States, residing at Farrell, in the county of Mercer and State 5 of Pennsylvania, have invented new and useful Improvements in Sleds, of which the following is a specification.

My present invention has reference to an improved construction of sleds.

10 My object is to produce a sled that has in addition to the usual side runners, a central runner which will facilitate rather than retard the gliding of the sled over slippery surfaces.

15 A further object is the production of a sled which is provided with braking means for stopping the sled to avoid any liability to danger to the operator or to the sled.

The foregoing, and other objects which 20 will appear as the nature of the invention is better understood, may be accomplished by a construction, combination and operative arrangement of parts, such as is disclosed by the drawings which accompany and 25 which form part of this application.

In the drawings:

Figure 1 is a side elevation of a sled constructed in accordance with this invention.

Figure 2 is a top plan view thereof.

30 Figure 3 is a bottom plan view thereof.

Figure 4 is a sectional view on the line 4—4 of Figure 2.

Figure 5 is a sectional view on the line 5—5 of Figure 2.

35 Figure 6 is a sectional view on the line 6—6 of Figure 2, and illustrating the chain brake in braking position.

With slight alterations that will reinforce and strengthen sleds of the ordinary construction, my improvement may be attached 40 thereto.

Referring now to the drawings in detail, the numeral 1 designates runners on which is secured a top board or seat 2. The top edges 45 of the runners 1 are recessed to receive therein spaced transversely arranged connecting cleats 3, 4 and 5 respectively, the seat or top 2 being also secured to the said cleats. In addition to the cleats 2 the runners 1 near the 50 front and rear ends thereof, and at points near or adjacent to the center of the said runners have additional transversely arranged reinforcing cleats or bars 6 and 7 respectively.

The above recited elements are constructed of wood, but the runners 1 are provided with the usual surface contacting members or runners proper.

Arranged centrally between the side runners 1 and partly underlying the top or seat 2, as well as projecting a suitable distance beyond the front ends of the said side runners is a guide runner 8. The runner 8 has its upper edge, at its rear corner notched, as at 9, the lower wall provided by the notch contacting with the under face of the cleat 4. The upper edge of the guide runner 8, opposite the cleat 5 is provided with a depression of a materially greater length than the width of the said cleat 5, and the depth 60 of the depression is also less than the thickness of the said cleat 5. In this depression, indicated by the numeral 10 there is centrally arranged a projecting bolt 11. The bolt 11 is secured to the guide runner 8 in 65 any desired or preferred manner, the same being in the nature of a king bolt and entering a socket 12 provided in the under face of the cleat 5. The guide runner, forward of the 70 king bolt is approximately centrally formed with an elongated transverse opening 13 that receives therethrough the cleat or bar 6. The opening 13 is of a materially greater length 75 than the width of the cleat or bar 6, but the contacting engagement of the lower wall of 80 the cleat with the lower wall provided by the opening 13 prevents the upper edge of the guide runner contacting with the seat or top 85 of the sled. This is also true with respect to the engagement of the wall provided by 90 the notch 9 and the cleat 4. Thus it will be manifest that the guide runner is not only pivotally connected to the sled proper but being out of contacting engagement with the top or seat thereof is permitted a swing- 95 ing movement on the pivot or king bolt 12, and such movement is not materially restricted by the contacting engagement of the walls of the opening 13 and the notch 9 with the cleats 6 and 4 respectively. The 100 ground contacting surface of the runner is steel bound.

On the front of the guide runner 8 at the upper and outer corner thereof there is a laterally extending bar 14 to the ends of 105 which the pull cord for the sled is attached. The bar 14 also serves as a rest for the feet of the user of the sled, and a pressure ex-

erted on either end of the said bar will cause the swinging of the guide runner so that the sled can be properly guided over a surface.

5 Secured, as at 15, to the sides of the guide runner 8, forward of the opening 13 in the said runner, are the ends of a chain 16. This chain provides the brake for the sled. On one side of the guide runner, near the front 10 or nose thereof there are guides 17 and 18 respectively for a rod 19. The rod has its outer end offset and hook shaped, as at 20, whereby to sustain the chain 16 against the front or nose of the guide runner, when the 15 said chain is brought to such position. The rod 19 has its inner end bent at a downward angle as at 21 and its outer portion is offset, as at 22. The angle portion 21 of the bar is guided in the bracket 18, and the said bar 20 has connected thereto one end of a spring 23, the second end being secured, as at 24 to the side of the guide runner. The bar 19 is in the nature of a trigger or catch member, and a pressure by the foot of the operator on the 25 sled will move the bar 19 outward against the tension of its spring, causing the hooked end of the said bar to release the chain, permitting the chain to drop by gravity on to the surface over which the sled is traveling, 30 and when brought beneath the auxiliary runner the chain will serve as an effective brake for the sled whereby the sled may be brought to a speedy stop to avoid danger.

It is believed that the foregoing description, when taken in connection with the drawings will fully set forth the construction, operation and advantages of my improvement, but it is to be understood that the showing and description refer only to a 35 satisfactory embodiment of the improvement

as it now appears to me, and that I am entitled to make all such changes therefrom as fall within the scope of what is claimed.

Having described the invention, I claim:—

45 1. The combination with a sled, of an auxiliary runner centrally pivoted thereto having its rear terminating inward of the rear of the sled and its front projecting beyond the front of the sled, means between the sled and the auxiliary runner holding the latter out of contacting engagement with the top of the sled, a laterally extending bar secured to the outer end of the guide runner and providing a foot rest and a guide bar, 50 a chain having its ends secured to the sides of the auxiliary runner, and spring influenced means at the front of the auxiliary runner engaging the chain for normally holding the same from ground contacting 55 position, said means including an offset portion to be engaged by the foot of the operator resting on said guide bar.

2. The combination with a sled, of an auxiliary runner pivotally secured thereto and projecting beyond the front thereof, a guide bar on the outer end of the auxiliary runner, a chain having its ends secured to the sides of the guide runner and designed to be normally arranged around the front edge 60 of the auxiliary runner, a spring influenced rod having an offset hooked end designed to contact with the front of the auxiliary runner and to hold the chain elevated, said rod having its inner end extended downwardly 65 and from thence outwardly to provide a contact element for the foot of the operator resting on the guide bar.

In testimony whereof I affix my signature.

JAMES E. MATTHEWS.
